ATTORNEYS

UNITED STATES PATENT OFFICE

JAMES FRANK WILLIAMS, OF NEW YORK, N. Y., ASSIGNOR TO RAMP BUILDINGS CORPORATION, OF NEW YORK, N. Y., A CORPORATION OF DELAWARE

BUILDING

Application filed July 26, 1929. Serial No. 381,238.

This invention relates particularly to garage buildings of the type having storage floors located at different levels and connected by ramps over which the automobiles 5 may be driven under their own power from floor to floor in order to reach their respective storage spaces. An important object of the invention is to provide, in such a garage, a floor and ramp arrangement providing a 10 low ascent grade between the storage spaces located at different levels, without reducing the storage capacity of the building.

Other objects of the invention will appear hereinafter.

15 In the drawing, Fig. 1 is a horizontal section taken on the line 1—1 of Fig. 2;

Fig. 2 a vertical, longitudinal section taken on the line 2—2 of Fig. 1;

20 Fig. 3 a vertical, transverse section taken on the line 3—3 of Fig. 1; and

Fig. 4 a vertical, transverse section on the line 4—4 of Fig. 1.

The garage is represented as having an elongated, rectangular floor plan defined by 25 a front wall 1, rear wall 2, and side walls 3 and 4. This plan may be varied, however. A group of superposed level floors 5 occupy the front portion of the plan, extending along the front wall 1 the entire distance between the side walls 3 and 4. At the rear of 30 the level floors 5 are two groups of superposed, inclined floors 6 and 7 of material length. These two groups extend side by side and each fills half, or substantially half, 35 of the remaining area of the ground plan at the rear of the floors 5. The floors 6 of one group are joined in succession to the rear edges of the floors 5 and extend upwardly and rearwardly therefrom with a comparatively slight inclination clear to the rear wall 2. The floors 7 of the other group are also joined in succession to the rear edges of all 40 of the floors 5 except the lowermost one, which is at the ground level. From their connections with floors 5 the floors 7 extend downwardly and rearwardly clear to the rear wall 2 with a comparatively slight inclination in a reverse direction with respect to the 45 inclination of floors 6. These two groups of oppositely inclined floors are located en-

tirely at opposite sides of a vertical, central division plane, extending straight fore and aft of the building and are shown as separated by a wall 8 disposed in said plane. This wall may, however, be omitted or may 55 be replaced by an open structure.

Spaced a material distance rearwardly from the level floors 5 is a group of superposed, similarly inclined ramps 9, spaced inwardly from the rear wall 2 and lying entirely within the plan of the inclined floors 6 and 7. The rear end portions of floors 6 and 7 are disposed at staggered elevations and the ramps extend transversely through an opening in the partition wall 8 and join adjacent 60 ones of said staggered floors in succession.

All of the floors 5, 6 and 7 are represented in the present showing as being both driveway and storage floors. Some of the storage space may, however, be devoted to other uses. 70 As shown, each inclined floor 6 is provided with a longitudinal central driveway space 10 which extends the full length of said floor and opens directly into a driveway space 11 extending straight forward upon the connected floor 5 to the front wall 1. The front wall is provided with a doorway 12 opening into the driveway 11 of the lowermost floor 5 at the ground level. Similarly, each inclined floor 7 is provided with a longitudinal, 75 central driveway space 13 which opens into an alining driveway space 14 upon its connected floor 5. Each floor 5 is also provided with a driveway space 15 which transversely connects the driveways 11 and 14 and 80 occupies a position spaced from the front and rear edges of the floor. The ramps 9 extend equal distances at opposite sides of wall 8 and open directly into driveways 10 and 13. They are merged gradually with 85 said driveways along curved lines, as indicated at 16.

Each of the inclined floors 6 and 7 is provided with rows of automobile storage spaces 90 extending along the entire length thereof at both sides of the longitudinal driveways 10 and 13. Similarly, each floor 5 is provided with storage spaces along both sides 95 of the driveway spaces 11, 14 and 15.

An automobile to be stored upon an upper 100

floor is driven into the building through the doorway 12, then rearwardly along the driveway space 11 of the ground floor, upwardly along the driveway 10 of the connected inclined floor 6, upwardly along the 5 connected ramp 9 to the connected inclined floor 7 and still upwardly along the driveway 13 thereof to the driveway space 14 of the second level floor 5. If the automobile is required to ascend still farther in order to 10 reach its assigned storage space it is driven along the transverse driveway 14 of said second floor and along the driveway 11, and the ascending driveway 10 to repeat the circuit just described until its storage space is 15 reached. When leaving the building the automobile traverses this path in the reverse direction. All turns are in the same direction in either ascent or descent and thereby 20 confusion is avoided and the traffic through the building may be sped up.

My floor and ramp arrangement provides a continuous and substantially spiral vehicular path through the building. The grade of this path is extremely low owing to the fact 25 that it is shared by the long, oppositely inclined floors 6 and 7 and by the ramps 9. The inclination of floors 6 and 7 may be made very slight so that they will be in no 30 way objectionable as storage floors. The easy ascent grade is attained without any sacrifice of valuable storage space as the driveways along the floors and ramps take up no more space than do the driveways ordinarily required upon a flat garage floor of 35 material area.

While I have shown and described a very satisfactory form of my invention, I do not wish to be limited strictly to this disclosure 40 but reserve the right to make such changes in structure and adaptation as will lie within the scope of the claims.

What I claim is:

1. A garage building comprising a group 45 of superposed, level storage and driveway floors overlying one ground area; a group of superposed, inclined storage and driveway floors overlying another ground area and leading upwardly to said level floors and 50 joined thereto in succession; a group of superposed, inclined storage and driveway floors overlying another ground area, alongside said first group of inclined floors, inclined reversely to the inclination of the latter and joined to the level floors in succession 55 and leading upwardly therefrom; and ramps successively connecting the inclined floors of one group to the adjacent inclined floors of the companion group at points spaced a material distance along their inclination from 60 said level floors and completing a continuous and substantially spiral driveway leading upwardly through the building.

2. A garage building comprising a group 65 of superposed, level driveway floors over-

lying one ground area; a group of superposed, inclined storage and driveway floors overlying another ground area and leading upwardly to said level floors and joined thereto in succession; a group of superposed, inclined storage and driveway floors overlying another ground area, inclined reversely to the inclination of the floors of said second group and joined successively to said level floors and leading upwardly therefrom; and ramps successively connecting the inclined floor of one group to the adjacent inclined floors of the other group at points spaced a material distance along their inclination from said level floors and completing a continuous and substantially spiral driveway leading upwardly through the building. 70 75 80

3. A garage building comprising a level lower floor overlying one ground area; a level upper floor overlying said lower floor; an inclined storage and driveway floor overlying another ground area, joined to said lower floor and leading upwardly therefrom; an inclined storage and driveway floor overlying another ground area, inclined reversely to the inclination of said other inclined floor, and joined to and leading downwardly from said upper floor; and a ramp connecting said reversely inclined floors at a point spaced materially along their inclination from said level floors and completing a continuous and substantially spiral driveway leading from said lower floor to said upper floor. 90 95

4. A garage building comprising a lower 100 floor overlying one ground area; an upper floor overlying said lower floor; an inclined floor overlying another ground area and joined to said lower floor and leading upwardly from it; an inclined floor overlying 105 another ground area alongside said first inclined floor, inclined reversely to the latter and joined to and leading downwardly from said upper floor; and a ramp transversely connecting said inclined floors and completing a continuous, low grade and substantially spiral driveway leading from said lower floor to said upper floor, one of said inclined floors having automobile storage spaces along its inclination. 110 115

5. A garage building comprising a lower floor overlying one ground area; an upper floor overlying said lower floor; an inclined floor overlying another ground area and joined to said lower floor and leading upwardly therefrom; an inclined floor overlying another ground area alongside said first inclined floor, inclined reversely to the latter and joined to and leading downwardly from said upper floor; and a ramp lying entirely within the ground plan of said inclined floors and transversely connecting them to complete a continuous, low grade and substantially spiral driveway leading from said lower floor to said upper floor, one 120 125 130

of said inclined floors having automobile storage spaces along its inclination.

6. A garage building comprising a level lower storage and driveway floor overlying one ground area; a level upper storage and driveway floor overlying said lower floor; an inclined storage and driveway floor overlying another ground area and joined to said lower floor and leading upwardly from it; an inclined storage and driveway floor overlying a ground area alongside that of said first inclined floor, inclined reversely to the latter and joined to and leading downwardly from said upper floor; and a ramp lying entirely within the ground plan of said inclined floors and transversely connecting them to complete a continuous and substantially spiral driveway leading from said lower floor to said upper floor.

7. A garage building comprising a level lower storage and driveway floor overlying one ground area; a level upper storage and driveway floor overlying said lower floor; an inclined storage and driveway floor overlying another ground area and joined to said lower floor and leading upwardly from it; an inclined storage and driveway floor overlying a ground area alongside that of said first inclined floor, inclined reversely to the latter and joined to and leading downwardly from said upper floor; and a ramp lying entirely within the ground plan of said inclined floors and transversely connecting them to complete a continuous and substantially spiral driveway leading from said lower floor to said upper floor, the inclined floors being provided with automobile storage spaces along both sides of said driveway.

8. A building structure comprising a group of superposed, level floors overlying one ground area; a group of superposed, inclined floors overlying another ground area and leading upwardly to said level floors and joined thereto in succession; a group of superposed, inclined floors overlying another ground area, alongside and parallel to said first group of inclined floors, inclined reversely to the inclination of the latter and joined to said level floors in succession and leading upwardly from them; and ramps lying entirely within the ground plan of said two groups of inclined floors, transversely connecting the latter at points spaced a material distance along their inclination from said level floors and forming, with said level and inclined floors, a continuous and substantially spiral path leading upwardly through the building.

9. A garage building comprising a level lower floor overlying one ground area; a level upper floor overlying said lower floor; an inclined storage and driveway floor overlying another ground area joined to said lower floor and leading upwardly therefrom; an inclined storage and driveway floor

overlying another ground area, inclined reversely to the inclination of said other inclined floor, and joined to and leading downwardly from said upper floor; and a transverse ramp having driveway connections with said reversely inclined floors at points spaced a material distance from said level floors and completing a driveway between said floors.

10. A garage building comprising a group of superposed driveway and storage floors overlying one ground area; a second group of superposed inclined storage and driveway floors overlying another ground area and leading upwardly from said first group of floors and joined thereto in succession whereby each of the first group of floors will be joined to and merged directly with one of the inclined floors of said second group; and a ramp connected to each of the inclined floors at a distance from the point where said inclined floor joins and is merged with its connected floor of the first group, said ramp connecting the inclined floor of the second group to the next higher floor of the first group.

In testimony whereof I hereunto affix my signature.

JAMES FRANK WILLIAMS.
